UNITED STATES PATENT OFFICE.

CHARLES G. SARGENT AND FRANK L. FURBUSH, OF WESTFORD, MASSACHUSETTS, AS-SIGNORS TO C. G. SARGENT'S SONS CORPORATION, A CORPORATION OF MASSACHUSETTS.

METHOD OF DRYING SOAP CHIPS AND APPARATUS FOR CARRYING OUT THE SAME.

Application filed June 16, 1924. Serial No. 720,188.

This invention relates to the drying of chipped soap. Although the soap is delivered in the form of films or ribbons in this machine they soon take the form of chips by breaking up as they dry.

The principal objects of this invention are to avoid the indiscriminate circulation of the air by disc fans through all parts of the drying chamber and blowing it directly against the soap on a plurality of conveyors, thus treating the soap to the same blast of air whether it has been previously subjected to any drying operation or not. By introducing the hot air in that way without any definite path of circulation, the drying is performed in an indiscriminate way without any regard for the fact that the soap is likely to be melted by being subjected to a temperature too high upon its entering the machine and to dry on the surface or case harden and be discolored. We avoid these difficulties by subjecting the soap chips to a succession of drying actions of different degrees.

In the preferred form of the invention the soap passes three times through the drying chamber, being exposed to a moderate temperature when it enters and then to a higher temperature during its second entry and finally a maximum temperature during its final passage through the chamber which is the period at which the soap is being discharged.

For the purpose of accomplishing these results the hot air is driven into the drying chamber in a series of currents under the lowest conveyor which discharges the chips. The soap on this one therefore is subjected to the full temperature of dry heated air. As the air passes through this conveyor it takes up moisture from the soap and also is reduced in temperature. It then passes immediately to the next conveyor and through the soap thereon, subjecting that soap to air at a lower temperature, but still one considerably high, and containing some moisture. Finally the air after having been cooled and moistened further in this way, encounters the soap on the first conveyor by which it is introduced into the machine and heats that to a moderate temperature so that it cannot be melted by it or cannot dry rapidly on the surface and discolor. The invention also involves other features of

air circulation as well as the cooling of the soap chips as they are discharged from the drying chamber and features of construction and combinations of parts of the mechanism.

Reference is to be had to the accompanying drawings, in which—

Fig. 1 is a side view of an apparatus constructed for carrying out this invention;

Fig. 2 is a transverse sectional view through the drying chamber on the line 2—2 of Fig. 1; and

Fig. 3 is a transverse sectional view through the cooling chamber on the line 3—3 of Fig. 1.

We have shown the invention as carried out in a three apron drier. This drier may be of any desired length, having six, eight or ten sections, but it is characterized by the fact that it is provided with an upper endless apron 10 which receives the material at the left hand end in Fig. 1 and drops it over the roll 11 at one end on which the apron is carried on a second apron 12 at a lower level which travels in the opposite direction as indicated by the arrow thereon. This apron carries the material back to the feed end of the drier and drops it over the roll 13 on the lower or discharge apron 14 which travels back in the same direction as the apron 10. This apron carries the stock out to the discharge end of the machine. The aprons so far described are well known in drying machines and we have not described any particular method of driving them as any ordinary method can be used. But they are driven so that each succeeding apron is driven at a slightly reduced speed to compensate for full shrinkage of the soap as it dries. This allows for practically even layers of chips on all aprons. We have provided a feed apron 15 connected with the apron 10. On this apron the soap ribbons or films are dumped from the machine in which they are produced, or from another conveyor, so as to be fed in the direction of the arrow on the conveyor 10.

The drying machine in which the conveyors 10, 12 and 14 are located has a longitudinal heating chamber 16 along one side provided with a series of longitudinal steam pipes 17 which are heated by steam in any ordinary way. The heated air from this chamber is drawn out through a long opening 18 along the bottom entering the drying

chamber 19 below the lowest of the three aprons located therein. All of the air is drawn up through the lower apron 14, while fresh from the heating pipes, thus heating the soap chips on this apron to the maximum. This is the final heating of the soap. Then the somewhat cooled and moistened air is forced through the soap on the apron 12 and finally the first apron 10 and part of it through side discharge passage 21 into the chamber 23. In this chamber are circulating fans 24 which draw the air up through the three conveyor aprons and then discharge it down through openings 25 back into the heating chamber. Several of these fans 24 are located along the top of the coil chamber and each of them performs the function above mentioned.

Some of the air enters into a conduit 28 which extends throughout the length of the drying chamber at the top and has an inlet slot throughout its length. The exhaust fan 26 at the feed end receives the moisture laden air from this conduit and discharges it upwardly through an exhaust outlet 27 out of the machine. In this way the air is heated, filled with moisture by going through the soap, then part of it drawn down back into the heating coils and circulated over again and finally discharged through the outlet 27 as stated. In this way the air encountering the soap chips when they first enter the machine is more moderately heated and also more moist than that they encounter as they pass along further in the machine on the first conveyor. Therefore they are not suddenly heated too hot nor dried too rapidly as they enter the drier but are both heated and dried gradually, so that they do not melt or case harden.

The chips are subjected to these drafts of heated air until the moisture is all taken out of them, but by that time they are heated up to a high temperature, of course below the melting point of the material of which they are made. The next step of the process consists in running the apron 14 out materially beyond the apron 12 so that it goes through a cooling chamber 30. Here it encounters drafts of air delivered from chambers 31, 32 and 33 located on both sides and below the cooling chamber 30. Each chamber is provided with water pipes 34 through which the water is driven by a pump. A fan 35 forces air in from the outside through these various chambers and around the pipes into contact with the heated soap chips on the conveyor 14 so as to cool down these soap chips. Baffle plates 36 are employed to force the air from the chamber 31 down into close contact with the chips on the apron. All the air thus driven in passes out through a stack 37 into the atmosphere. Soap chips thus thoroughly dried and cooled are delivered from the machine over the end of the conveyor 14 at the right hand end as shown in Fig. 1.

In this way the chips are thoroughly dried by a gradual process. The heat of the air in the various parts of the drier is conserved as much as possible and finally the air is discharged in a somewhat cool condition, thus providing for an efficient use of the heat.

The cooling chamber is made entirely separate and the currents of air therethrough are separate from the heated air in the other chamber as there is little space around the apron 14 in which there may be any communication. Even at this time the heated air currents in the chamber 19 near the end 70 and the cool air currents in the chamber 30 adjacent thereto move in the same direction and are forced by the action of the fans to move in that direction so that there is very little occasion for them to mix at the point 75 where they could pass back and forth as there is no material difference in pressure at adjacent points in the two chambers.

This affords an economical and efficient method of drying soap chips and at the same time delivering them in a cooled condition so that they can be packed in boxes ready for immediate shipment or storage and there will be no danger that when packed they will retain any heat sufficient to 80 cause them to adhere to each other or to flatten out and pack down. This also avoids all necessity of delaying the packing process after the drying process is completed. They can be carried on practically continuously 85 which is an important feature.

Although we have illustrated and described a specific order of steps and a specific form of drying machine, we are aware of the fact that this principle can be carried out by anyone skilled in the art without following exactly the procedure or employing the specific form of drying machine, shown and described without departing from the scope of the invention as expressed 90 in the claims.

Therefore we do not wish to be limited to all the details of construction but what we do claim is:—

1. The method of drying soap chips which 115 consists in carrying them through a chamber in a series of stages, running them at each stage at a speed slightly less than that of the one in which they have previously traveled, subjecting them to currents of 120 heated air while traveling in said chamber, directing said currents so as to heat the chips gradually as they travel along, moving them from the chamber after they are thoroughly dried, and immediately subjecting them to currents of cold air adjacent to the heating chamber.

2. In an apparatus of the character described, the combination with a drying chamber, a plurality of endless aprons 125

therein for receiving the soap chips and discharging them alternately at opposite ends of the chamber from one apron to another, the bottom apron extending materially beyond the other aprons at the discharge end for carrying the soap chips out of the drying chamber, and means in the drying chamber for forcing currents of heated air up through the several aprons to dry the chips 10 thereon, of a cooling chamber adjacent to the drying chamber through which the lower apron extends, and means in the cooling chamber for forcing cooled air up through the lower apron and down upon the upper surface thereof where it passes through the 15 cooling chamber to cool the heated chips before they are discharged from the lower conveyor.

In testimony whereof we have hereunto affixed our signatures.

CHARLES G. SARGENT.
